Hollings.

UNITED STATES PATENT OFFICE.

EDWARD A. TUCKER, OF WINCHESTER, MASSACHUSETTS.

ROADWAY OR PAVEMENT.

Application filed January 10, 1924. Serial No. 685,370.

This invention relates to roadways or pavements, more particularly to concrete-surfaced roadways or pavements, and consists in improvements which are designed to 5 lengthen the life thereof.

A concrete surfaced road tends to deteriorate in part because of the incapacity of the surface to yield and adapt itself without fracture to changes either permanent or 10 temporary and seasonal in the position of the underlying roadbed. Under the action of frost, or due to a natural settling or upheaval of the roadbed, certain parts thereof are apt to become relatively depressed and 15 others elevated. This compels the surface to bend more or less, and due to its inability to flex sufficiently to adapt itself to the changed position of the underlying bed without fracture, a crack starts where the 20 bending or flexing is the greatest. Once started this crack soon opens and grows into a large fissure under the travel which the roadbed carries.

The object of the present invention is to 25 produce a roadway or pavement having a hard, durable, concrete surface, with sufficient flexibility to enable it to adapt itself without fracture or the formation of surface cracks to the changes in the underlying 30 roadbed which are commonly incident to a well built roadway. In the illustrative embodiment of the invention this is accomplished by providing the roadway with a surface composed preferably of individual, 35 pre-cast, concrete units of relatively great length as compared with the lesser transverse dimension, each unit being so reinforced, and preferably by a multiplicity of longitudinal reinforcing members distributed 40 with substantial uniformity throughout its cross section, as to provide a concrete unit capable of undergoing abnormal deflection and elongation without fracture. The roadbed may be prepared in the usual 45 way with a concrete foundation and the surface then added by applying the flexible, pre-cast, reinforced concrete surface units to the top of the concrete bed while the latter is still soft, the surface units being preferably both bonded and anchored to the concrete bed to produce therewith a reinforced concrete section in which the reinforcement 50 is utilized in a most efficient manner. Or,

by employing suitable means to hold the pre-cast, surface units in place, they may 55 be utilized in connection with a roadbed prepared without a concrete base, or with portions only formed of concrete.

The invention will be best understood by reference to the following description when 60 taken in connection with the accompanying illustration of one specific embodiment thereof, while its scope will be more particularly pointed out in the appended claims.

In the drawings:—

Fig. 1 is a cross section showing a roadway provided with a concrete base and a concrete surface constructed in accordance with one form of the invention;

Fig. 2 is a longitudinal section of a portion of the roadway illustrated in Fig. 1;

Fig. 3 is a perspective on a larger scale showing one end, partly broken away, of a pre-cast, concrete, surfacing unit reinforced to provide an abnormal amount of 75 flexibility;

Fig. 4 is a cross section taken through one of the surfacing units illustrating one form of an anchoring device;

Fig. 5 is a cross section of a roadway utilizing pre-cast, surface units slightly modified from the construction shown in Fig. 1 and applied to a roadbed having other than a concrete base;

Fig. 6 shows in detail one means of holding the ends of the pre-cast, surfacing units along the edge of the roadway shown in Fig. 5;

Fig. 7 is a longitudinal section of a portion of the roadway shown in Fig. 5; and 90

Fig. 8 is a detail illustrating the use of a preferably pre-cast joint for the center of the roadway, where a roadbed of the type shown in Fig. 5 is employed.

Referring to the drawings and more particularly to the illustrative embodiment of the invention shown in Figs. 1 to 4 inclusive, I have there shown a roadway in which there is utilized for the concrete surface a series of pre-cast, concrete, plank-like members 11 which may be laid transversely on the upper surface of the concrete bed 13, the latter being poured in place and resting on the underlying bed 15. The latter may be constructed of broken stone with suitable 100 filling, or may have any other usual and 105

desired formation according to requirements, and the concrete base 13 may be of any desired depth or thickness. The bed having been thus prepared the precast, surfacing units are laid on the poured concrete top thereof while the latter is still soft and adapted to have embedded therein suitable anchoring devices presented by the under side of the surface units 11.

10 Any suitable anchoring means may be employed, but herein there are provided for that purpose a series of wire loops 17 depending from the bottom of each plank-like unit and having their ends held within 15 the body of the unit by the pre-casting operation and preferably, though not necessarily, anchored or secured to the reinforcement thereof.

In the case of a narrow roadway or pavement 20 the individual surfacing units may extend entirely across the same, but in the illustrative form of the invention the roadway, both as to the concrete base and the surface, is divided transversely into two 25 longitudinal sections, the individual surfacing units extending across each section and having their ends separated at the center of the roadway by a small space which is filled with cement or other suitable substance to 30 form a continuous center joint 19 between the two sections. The two sections of the concrete bed 13 may be united at intervals by dowel pins 21 (see Fig. 1) or other reinforcing means adapted to tie them together.

The surfacing units may be laid with their sides in contact, but preferably they are located to leave narrow intermediate gaps which, after the units are laid, are filled 40 with cement to form transverse joints 23 between individual units, so that the entire top forms a smooth, unbroken surface comprising the individual pre-cast members united to the top of the poured concrete bed 45 and separated by the narrow, longitudinal and transverse joints referred to.

In preparing the concrete bed 13 the bottom thereof will preferably be poured with a mixture of cement, sand and rock, while the 50 top is formed of a finer mixture principally of sand and cement. This is brought to a smooth surface adapted to the desired contour of the road and suitable to have the surfacing units embedded in the top thereof 55 so as to develop by bond and anchorage a beam action in the combined section of base and surfacing unit. The top of the concrete bed may be poured slightly above its ultimate required height so as to permit the 60 units to be worked down into the bed to provide a smooth, finished top surface of the required contour and height. This process will result in forcing more or less cement up between the units and will result in partly or wholly filling the intermediate joints.

The individual surfacing units are preferably pre-cast with a system of reinforcement such as that described in my Patent No. 1,530,630 dated March 24, 1925. This is adapted to provide a unit having a high 70 ratio of length to least dimension and capable of undergoing abnormal deflection and elongation. In forming such unit reinforcement is provided consisting preferably of a series of layers of metallic reinforcement, such as steel or iron, distributed with substantial uniformity throughout the cross section of the unit. The reinforcing members of each layer may consist of small rods or wires, or a fabric having longitudinal 75 transverse wires, but herein I have shown the same in the form of successive layers of longitudinal wires 25 which are separated at intervals by the interposed transverse bars or members of a grid or netting 80 27. Such a grid or netting may be employed at intervals lengthwise the unit, but its function is primarily to relatively space and locate the rods in the mould during the casting operation and it is not essential as a 85 matter of reinforcement.

While the invention is not restricted to the dimensional limits of the reinforcing unit, by way of illustrative example the member may be assumed to have a cross section 8 x 13 $\frac{1}{8}$ inches, the longitudinal reinforcing members being formed of approximately No. 12 wire and arranged in six layers, the reinforcement in adjoining layers being preferably in staggered relation to 90 better distribute the reinforcement and successive layers in the illustrative example having respectively five and six members each. In the illustrative example, furthermore, the longitudinal reinforcing members of successive layers are spaced apart on centers by a distance equivalent to about two 95 diameters of the wire, so that each layer of the concrete considered from the top to the bottom of the unit will be within the effective bonding region of one of said longitudinal reinforcing members. To achieve this 100 result the layers of reinforcement should preferably be separated by an amount equivalent to not more than five diameters 105 on centers. It is unnecessary that the spacing of the longitudinal rods of each layer in the direction at right angles to the least dimension (or crosswise the plank) be less than a distance equivalent to three diameters. It will be understood that these 110 dimensional examples given are illustrative merely.

In arranging the reinforcement in the mould and in pouring the concrete, there is 115 preferably allowed only a slight covering of the concrete over the upper and lower layers of reinforcement so as to give the necessary embedment thereof.

The effect of this disposition of the re- 120

inforcement is to distribute the steel or other metallic reinforcing strands throughout the entire cross section in a series of planes or layers and symmetrically with reference to 5 the axis, but spaced closely enough so that the concrete in any plane or layer at right angles to the least dimension is held together and rendered capable of greatly increased elongation in the same manner as in concrete 10 immediately surrounding a reinforcement member.

In the usual method of reinforcement, where the latter is concentrated and placed unsymmetrically with relation to the axis of 15 the concrete member, only those portions of the concrete near such reinforcement, and ordinarily near the outer surface, are made capable of increased elongation, whereas in the illustrative embodiment of the invention 20 all portions are made similarly capable of increased elongation because of the substantially uniform distribution of the steel throughout the entire cross section. Furthermore, the capacity for elongation of the 25 outer surface is further increased because of the fact that these portions are helped out or relieved of some of the strain by the concrete and strands in each adjacent layer which, being of the same capacity and under 30 less strain because nearer the neutral axis, will help hold the outer fibres or strands from rupture and at a higher strain than such fibres or strands would stand if only the surface of the concrete were reinforced. 35 A surfacing unit reinforced in the manner described is qualified to withstand an abnormal deflection without detriment.

In a concrete unit reinforced as in the present case by a multiplicity of small 40 strands or other similar reinforcing members, it is sometimes difficult to eliminate voids and provide a dense, homogeneous body of concrete. It is important to maintain the separation and spacing of the reinforcing members and to eliminate all 45 voids. In practice this may be attained by fixing in the mould a series of separating grids 27 or their equivalent, closely fitting the strands and qualified to hold them in 50 fixed relative positions, and then agitating the moulds during and following the pouring of the concrete, thus causing the concrete to settle down and completely fill all spaces between the reinforcement while at the same 55 time avoiding displacement of the strands from their assigned positions.

The application of the pre-cast concrete unit which is bonded to the concrete base produces a section capable of developing a 60 beam action in the whole cross section. When this pre-cast member is bonded to the concrete base the method of distribution of the steel members in the pre-cast unit produces a reinforced concrete section in which is 65 utilized the full tensile strength of the steel

and also, in a dependable way, the full tensile strength of the concrete,—both acting together. The method of distributing the strands of steel in the pre-cast member 70 also produces, when the member is bonded to the base, a unit having greater flexibility than would be obtained if reinforced with the same amount of steel in a single layer. This permits a relatively small amount of steel to be used for road reinforcement, giving 75 the required flexibility to the surface, and at the same time the required strength to the entire road section considered as a beam.

Referring to Figs. 5 to 8 inclusive, I have 80 there shown the use of pre-cast, surface members in connection with a roadbed other than of concrete formation. In this case the roadbed 29 may be specially constructed for the purpose or may be the bed of an existing 85 roadway which it is desired to have surfaced or rebuilt. This is covered with a levelling or filling surface 31 of gravel, sand, tar or other material, the top of which is brought to a uniform level or grade, and has 90 applied thereto the surfacing units 33. These units are laid with their outer edges resting on the tops of concrete beams 35 and secured thereto by the concrete edge strip 37 and the bolts 39 set at intervals in the beams 95 35 and arranged to pass through perforations in the surfacing units and the strip 37. The edge beams 35 may be pre-cast but are preferably poured in place with the aid of 100 forms. The edge strip 37 is preferably pre-cast.

The surfacing units 33 are preferably formed with the system of reinforcement already described, which imparts a high 105 degree of flexibility thereto. In the case of a double section roadway as illustrated in the drawings, the abutting edges of the units may be united by any suitable kind of a joint. In the illustrative form of the invention the inner ends of each section are 110 grooved or flanged, as illustrated, so that when laid they present a longitudinal channel which is filled by a longitudinal center joint 41, the latter being preferably pre-cast and cemented in position, although, if desired, it may be poured in place. The units 115 may be laid with their sides in contact but preferably, as in the case of the roadway illustrated in Figs. 1 to 4 inclusive, they are laid with small intermediate spaces which are cement filled to provide transverse joints 120 43.

While I have herein shown and described for the purposes of illustration one specific embodiment of the invention, it is to be 125 understood that the same is not limited to the dimensional characteristics submitted by way of example, or to the form or relative arrangement of parts, or to the specific application herein made thereof, but that ex- 130

tensive deviations may be made from the illustrative embodiment of the invention all without departing from the spirit thereof.

I claim:

5. 1. In a roadway or pavement, the combination with a roadbed, of a surface comprising a series of reinforced concrete units laid thereon and secured thereto, each unit consisting of a member of relatively great 10 length compared to its least transverse dimension, and having longitudinal reinforcing members so distributed throughout its cross section as to bring each concrete layer lying transverse to the direction of said least 15 dimension within the effective bonding region of one of said reinforcing members to provide thereby a member adapted to undergo abnormal deflection.
2. In a roadway or pavement, the combination with a roadbed, of a surface comprising a series of reinforced concrete units laid thereon and secured thereto, each unit consisting of a member of relatively great 20 length as compared to its least transverse dimension, and having a multiplicity of longitudinal reinforcing members distributed with substantial uniformity throughout its cross section to provide thereby a unit reinforced throughout and adapted to undergo 25 abnormal deflection and elongation.
3. In a roadway or pavement, the combination with a roadbed, of a surface comprising a series of reinforced concrete units laid thereon and secured thereto, the reinforcement for each unit comprising longitudinal reinforcing members arranged in a series of layers, and the spacing of each layer in the 30 direction of least dimension of each unit being not greater than five diameters of the reinforcing member.
4. In a roadway or pavement, the combination with a roadbed having a concrete body, of a surface comprising a series of reinforced concrete units laid thereon and bonded thereto, each unit consisting of a member having longitudinal reinforcing elements distributed throughout the cross section thereof.
5. In a roadway or pavement, the combination with a roadbed having a concrete body, of a surface comprising a series of pre-cast, reinforced concrete units laid thereon and bonded thereto, each unit consisting of a member having longitudinal reinforcing 55 elements so distributed throughout its cross section as to bring each concrete layer of said unit within the effective bonding region of one of said reinforcing elements to provide thereby a member adapted to undergo abnormal deflection, and anchoring means for said members embedded in the concrete body of the roadbed.
6. In a roadway or pavement, the combination with a roadbed having a concrete body, of a surface comprising a series of pre- 60

cast, reinforced, concrete units laid thereon and bonded thereto, each unit consisting of a member having longitudinal reinforcing elements so distributed throughout its cross section as to provide a member capable of taking elongation in each component layer in a manner resembling that characteristic of a homogeneous beam.

7. In a roadway or pavement, the combination with a roadbed having a concrete body, of a surface comprising a series of pre-cast, reinforced, concrete units laid thereon and bonded thereto, each unit being of relatively great length as compared with its thickness and consisting of a member having distributed throughout substantially the entire cross section a series of reinforcing members in a multiplicity of layers, not less than four in number, serially arranged transverse the thickness of the surface unit whereby there is provided a surface with a roadbed capable of having elongation in each component layer thereof in a manner resembling that characteristic of a homogeneous beam.

8. A roadway or pavement having a concrete base, a series of precast surfacing units each of relatively great length as compared with the thickness, said units being reinforced by a multiplicity of longitudinal reinforcing members arranged in a series of planes transverse to the thickness of the unit, the distance between successive planes of reinforcement being not greater than five diameters of the reinforcing members, and said surfacing units being secured to the concrete base by bond and anchorage to form a combined section capable of developing a beam action.

9. A construction member having a concrete body and a precast, reinforced, concrete unit laid thereon and bonded thereto, said unit being of great length as compared with its thickness and consisting of a member having a multiplicity of longitudinal reinforcing elements so distributed throughout its cross section as to provide a member capable of taking elongation in each component layer in a manner resembling that characteristic of a homogeneous beam, said construction member providing a section capable of developing a beam action in its whole cross section.

10. A concrete roadway or pavement characterized by a concrete body having reinforcement concentrated closely adjacent to the surface of the roadbed but comprising reinforcing members arranged in a multiplicity of layers, not less than four in number, serially arranged transversely relative to the thickness of the roadbed.

In testimony whereof, I have signed my name to this specification.

EDWARD A. TUCKER.
